UNITED STATES PATENT OFFICE.

BENJAMIN A. MITCHELL, OF GARFIELD, UTAH, ASSIGNOR OF TWO-THIRDS TO MINNIE L. MITCHELL, OF MAGNA, UTAH.

VIBRATING SCREEN.

Application filed January 2, 1918. Serial No. 209,920.

To all whom it may concern:

Be it known that I, BENJAMIN A. MITCHELL, a citizen of the United States, residing at Garfield, in the county of Salt Lake 5 and State of Utah, have invented certain new and useful Improvements in Vibrating Screens, of which the following is a specification.

This invention relates to vibrating screens 10 and more particularly to screens actuated for sifting ore, sand, gravel and similar material.

This invention has for its general object an improved construction and arrangement 15 of parts which is durable, efficient and readily manufactured.

A more specific object is to provide an improved means for actuating screens and increasing their output.

20 Another object is to provide an improved vibrating means for actuating screens of this character.

Another object is to provide improved means capable of producing a harmonic motion of constrained amplitude in a constantly changing direction.

Still another object is to provide an improved arrangement for imparting vibrations to screens.

30 Other objects and advantages will in part be specifically pointed out hereinafter and in part obvious from the arrangements and constructions here set forth.

The invention accordingly consists in the 35 features of construction, combinations of elements and arrangement of parts which will be exemplified in the construction hereinafter set forth, and the scope of their application will appear in the appended claims.

40 For a more complete understanding of the nature and advantages of this invention reference should be had to the following detailed description, which describes the best 45 illustrative embodiments of this invention at present known to me, taken in connection with the accompanying drawing in which—

Figure 1 shows a sectional view taken transversely through my improved screening device on the line 1—1 of Fig. 3;

50 Fig. 2 shows an enlarged detail sectional view illustrating the method of mounting the screen in the frame;

Fig. 3 shows a longitudinal sectional view taken on the line 2—2 of Fig. 1 with parts 55 thereof broken away.

Referring now to the drawing, and to Figure 1 in particular, 10 denotes a frame having upper and lower end walls 11 and 12 and side walls 13 and 14. This frame serves as the supporting means for the screen 15 which is to be vibrated by the vibrating means at 25, arranged to have freedom of motion in all directions save for the restraint imposed by the connections 31 which connect it with the screen. The screen 15 may be of any suitable fabric having the desired mesh, wire cloth being in most instances preferable. The slotted pipes 16 on the frame 10 provide a suitable arrangement for gripping the screen 15 at two opposite edges and securing the same to the frame, such pipe being supported by flanges 13^a and 14^a of the frame.

The details of the arrangement for attaching the screen to the tube 16 will appear more clearly by reference to Fig. 2, in which the tube is shown as having a longitudinally extending slot 16^a adapted to receive the screen 15 which is looped around a longitudinally extending rod 17 within the tube, and has its edge portion 15^a drawn out again through the slot 16^a, so that when the two tubes 16 on opposite sides of the screen are separated, the sides of the screen are drawn away from each other, and pressure of the walls of the slots 16^a on the folds of the screen presses the folds against the rod 17 and increases the tightness of the grip of the tubes upon the screen. The tube 16 at one side of the screen is connected to the frame member 14 by means of one or more pins 18 engaging suitable apertures in the frame member, and the tube 16 at the other side of the frame is attached to one or more adjusting rods 19 extended through the side wall 13 of the frame and engaged by suitable adjusting devices, such as a hand wheel 20 having a threaded engagement with the end of the rod. By means of this adjusting device, the tension of the screen 15 may be regulated to any desired degree of tightness. The screen is preferably mounted for operation in an inclined position, as shown in Fig. 3, the inclination of the screen being adjusted by means of the supporting posts 22 comprising arcuate slotted plates connected together by clamping bolts 23 and supported on a base 24.

The vibrating means at 25 is driven by an electric motor 26 mounted stationarily on

2

the frame member 14 at one side of the device, which motor is a high speed machine having its shaft 26^a connected with the driving shaft 28 of this vibrating means through 5 a flexible coupling 27. The driving shaft 28 is journaled in the casing 29 of the vibrating means and has fixed thereon at 30 an unbalanced disc or other means whose mass centre is eccentric to the axis of rotation. 10 This disc may be formed by recessing or cutting away material at one side from an otherwise symmetrical disc, as shown at 30^a, so that the weight thereof is unevenly distributed with respect to the axis of rotation. 15 As a consequence when the shaft is rotated at high speed by the motor 26, rapid harmonic impulses of constantly changing direction are imparted to the casing 29 and transmitted therefrom to the supporting 20 screen 15 through the connections 31, which are secured both to the casing 29 and the screen 15 by suitable securing devices, as shown at 32 and 33. Two or more of the posts 31 are preferably employed, which 25 are preferably distributed substantially uniformly around the central point of the screen 15 as indicated. By reason of the tensioned support afforded the vibrating means by the screen the amplitude of the 30 impulses transmitted are not unlimited but constrained.

In operation, the screen 15, having been adjusted in a suitable operative position, is set into vibration by starting up the motor 35 26 which causes the vibrating means 25 to execute harmonic motion of constrained amplitude in a plane perpendicular to the plane of the screen, the same being positively imparted thereto through connections 31. The 40 material to be screened is then fed onto this vibrating screen which serves to effect a very thorough screening of the material passing thereover, the coarser parts passing downwardly over the lower edge of the 45 screen adjacent the lower wall 12 of the frame, which is preferably spaced from the lower end of the screen where the coarse materials are permitted to drop downwardly. The action of the screening device may be 50 regulated by varying the inclination of the frame, and also by varying the speed of the vibrator. The screen is preferably stretched tight similar to a drum head, the tension 55 preferably being such that the resultant period of full vibration for the screen is resonant with that of the vibrating device, and the motor or other driving device preferably has a very high speed. The method of attaching the screen to the frame permits 60 the use of vibrations having a very high frequency without loosening the supports of the screen, and it is found in practice that a much more perfect result is accomplished 65 because of the high frequency and regularity of the vibration than it has been possi-

ble to obtain with other apparatus intended for this purpose. The power used by the vibrator is very small, and at the same time it is easily possible to obtain four thousand or more vibrations per minute, for example. 70 It will be observed that the vibration set up by this device is a true vibration having undamped action devoid of beats, due to the synchronizing of the period of vibration of the screen with that of the vibrating device, 75 as distinguished from impulses and impacts, thus producing an efficient screening action and maintaining the meshes or openings of the screen in an unclogged condition. The vibrator may be supported independently 80 of the screen and connected thereto by flexible material such as piano wire instead of being mounted on posts as herein illustrated.

As many changes could be made in the 85 above construction and many apparently widely different embodiments of this invention could be made without departing from the scope thereof, it is intended that all matter contained in the above description or shown in the accompanying drawings shall 90 be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween. 95

What I claim is:

1. In apparatus of the class described, a screen, means for supporting said screen and maintaining a high tension therein, and means positively connected to said screen for producing minute circular vibrations 105 therein.

2. In apparatus of the class described, a screen, means for supporting said screen and maintaining it under tension, vibrating means supported opposite an intermediate 110 part of said screen and connected thereto for positively imparting a continuous series of minute circular movements of extremely small diameter directly to said screen in opposite directions and transversely to its plane of support, and means for operating said vibrating means.

3. In apparatus of the class described, a screen, a frame, means connecting said frame and said screen for adjusting the tension of said screen, vibrating means for producing minute circular movements in said screen independently of its frame, said vibrating means being connected to an intermediate 120 part of said screen, and means for operating 125 said vibrating means.

4. In an apparatus of the class described, an inclined screen held in a substantially stiff and rigid condition, a vibrating means producing a continuous vibration of vary- 130

- ing direction and a positive connection between said vibrating means and said screen for imparting vibrations thereto substantially perpendicular to the plane of the screen.
5. In apparatus of the class described, a screen, means for supporting said screen, supporting posts mounted on said screen between its edges, a vibrating means carried by said posts for producing a series of minute circular vibrations in said screen independently of its support, and means for operating said vibratory device.
6. In apparatus of the class described, a frame, a screen supported by said frame, a vibrator casing supported opposite an intermediate part of said screen and connected to said screen, an unbalanced rotary member mounted in said vibrator frame, and means for rotating said member and thereby imparting vibrations to said casing and said screen.
7. In apparatus of the class described, a frame, a screen stretched between opposite members of said frame, a rotary vibratory device supported on an intermediate part of said screen, and driving means having a flexible connection coupling the same to said vibratory device.
8. In an apparatus of the class described, a screen, a frame for supporting said screen in an inclined position, and means positively connected to said screen for producing circular vibrations in said screen independently of said frame.
9. In apparatus of the class described, a screen adapted to be vibrated, a movable vibrating means having a rotating mass center eccentric to the axis of rotation, and a positive connection from said vibrating means to said screen.
10. In apparatus of the class described, a screen, means for supporting the same in screening position, and a movable vibrating means having a rotating eccentric mass centre and provided with a positive connection with a portion of said screen whereby a harmonic motion of constantly changing direction is imparted in a plane perpendicular to the plane of said screen.
11. In apparatus of the class described, a screen, means for supporting the same in screening position, a movable vibrating means having a rotating mass centre and provided with connections to said screen for imparting thereto harmonic motion of constrained amplitude in a plane perpendicular to the plane of the screen, and means for drawing the screen to a tension whose period of free vibration is resonant with the period of the impressed harmonic motion.
12. In apparatus of the class described, an inclined screen supported in substantially fixed position, and vibrating means supported by said screen having a rotating eccentric mass centre for producing simultaneously in said screen a series of minute circular vibrations in planes perpendicular to the plane of the screen.
13. In apparatus of the class described, a screen, means for supporting said screen in an inclined position, and a movable vibrating means for producing continuous harmonic vibrations of constantly changing direction in said screen in planes perpendicular to the plane of the screen.
14. In apparatus of the class described, an inclined screen, a movable vibrating means actuated by internal centrifugal force for producing harmonic vibrations of constantly changing direction, and connections with said screen for transmitting the vibrations to said screen in planes perpendicular to the plane of the screen.
15. In apparatus of the class described, a screen stationarily supported in screening position, a vibrator having a rotating eccentric mass center disposed at one side of said screen, and means on said vibrator in operative engagement with said screen for imparting circular vibrations to said screen.
16. In apparatus of the class described, an inclined stationarily supported screen, and means for producing minute circular vibrations in said screen in planes perpendicular to the plane of the screen.
17. In apparatus of the class described, an inclined screen, stationary supporting means for maintaining said screen continually in a substantially inflexible stiff condition, and means for producing directly in said screen high frequency vibrations of minute circular motion in planes perpendicular to the plane of said screen.

In testimony whereof, I have subscribed my name.

BENJAMIN A. MITCHELL.
